CLAIM

The ornamental design for a ladder assembly, as shown and described.

DESCRIPTION

FIG. 1 is a top plan view of the ladder assembly design;
FIG. 2 is a bottom plan view of the ladder assembly design;
FIG. 3 is a front elevation view of the ladder assembly
design;

FIG. 4 is a rear elevation view of the ladder assembly design;
FIG. 5 is a left side elevation view of the ladder assembly
design;

FIG. 6 is a right side elevation view of the ladder assembly
design;

FIG. 7 is a front perspective view of the ladder assembly
design;

FIG. 8 is a rear perspective view of the ladder assembly
design;

FIG. 9 is a bottom perspective view of the ladder assembly
design;

FIG. 10 is a detailed right rear perspective view of an upper
portion of the ladder assembly design;

FIG. 11 is a detailed left rear perspective view of an upper
portion of the ladder assembly design; and,

FIG. 12 is a front perspective view of an alternative position
of the ladder assembly design with the ladder in a raised
position.

The broken lines in FIGS. 10 and 11 are boundaries of the
partial enlarged views where the claimed surfaces are cut for
purposes of enlargement. These broken lines form no part of
the claimed design.

1 Claim, 12 Drawing Sheets
